UNITED STATES PATENT OFFICE.

JAMES WEBB ROGERS, OF NEW YORK, N. Y.

ELECTRIC CONDUCTOR.

SPECIFICATION forming part of Letters Patent No. 279,189, dated June 12, 1883.

Application filed March 29, 1883. (No model.)

To all whom it may concern:

Be it known that I, JAMES WEBB ROGERS, a citizen of the United States, and a resident of New York, in the county of New York and State of New York, have invented certain new and useful Improvements in Electric Conductors, of which the following is a specification.

My invention relates to electric conductors for telephones, telegraphs, electric lights, electric transmission of power, and other purposes, and its object is to furnish a simple and cheap conductor that can be readily and quickly made in large quantities, and that shall have high conductivity with a maximum of tensile strength.

My invention consists of a thin longitudinal tape, ribbon, or strip of a metal of good conductivity—such as copper—supported by a wire of some metal of high tensile strength—such as steel or iron—which is wound spirally about the conductor, which serves to support the thin longitudinal ribbon or tape of copper when the latter is supported by insulators or other supports at a considerable distance apart, and to prevent such thin ribbon or tape from breaking.

It is well known that a thin tape or ribbon of metal is a better conductor of electricity than a solid wire having the same area of cross-section, because of the well-known tendency of the electric current to pass upon the surface of a conductor instead of through the body of the same. At the same time the materials whose conductivity is large—such as silver, copper, and gold—are deficient in tensile strength, so that, aside from the question of cost in the case of silver and gold, it would be impracticable to use them in the shape of thin ribbons or strips stretched between the places to be connected, although in the form of a ribbon or strip they would be of very high conductivity.

It is the aim of my invention to overcome this objection to the use of a strip or ribbon of copper stretched between distant points, and this I accomplish by combining with such strip a wire of steel or other metal of high tensile strength, wound spirally on the ribbon of copper, so as to support the same, but to still preserve the individuality of the copper con-

ductor as a longitudinal conducting tape or ribbon, while at the same time preventing it from being broken by the strain to which it would otherwise be subjected. If the copper tape or ribbon or the steel wire be insulated with an insulating-covering, the two could be used as independent conductors; or one could be used as a return-conductor for the other.

One of the forms that my invention may take in practice is shown in the accompanying drawing.

In the drawing, A indicates a thin longitudinal strip, tape, or ribbon of copper or other good conductor, and B a wire of steel or other material of high tensile strength, wound upon A. As before intimated, either the wire B or the ribbon A may be insulated. In the drawing the wire is shown as having an insulating-covering.

By my invention I secure great conductivity with a minimum of material. The conductor can be made cheaply and in large quantities from ordinary rolled copper ribbon or strips and steel wire, and with a minimum length of copper ribbon for the distance covered by the conductor.

If the wire on the tape be insulated, the conductor can be used as a leading and return conductor for telephones, and the disturbing effects of induction avoided.

What I claim as my invention is—

1. An electric-line conductor composed of a thin longitudinal copper ribbon or strip wound with a spiral supporting-wire of greater tensile strength.

2. An electric-line conductor composed of a straight copper ribbon or strip and a spiral supporting-wire of steel.

3. An electric-line conductor composed of a straight copper ribbon or strip, and a spiral supporting-wire of steel having an insulating-covering.

Signed at New York, in the county of New York and State of New York, this 27th day of March, A. D. 1883.

JAMES WEBB ROGERS.
